UNITED STATES PATENT OFFICE.

BURNHAM C. STICKNEY, OF RUTHERFORD, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed March 24, 1925. Serial No. 17,871.

This invention relates to the handling of webs of continuous forms in typewriting machines.

According to this invention, continuous forms, such as used in an Underwood fan-fold machine, can be handled and typed upon in a standard Underwood machine with little or no alteration thereof. It will be understood, however, that the device herein disclosed may also be used in connection with any other typewriting machine of the front-strike type.

One of the features of this invention relates to the provision of means for facilitating the handling of continuous forms in a standard Underwood typewriting machine.

Another feature of this invention relates to the provision of a chute through which the web is inserted to control it during the typing and cutting-off operations.

Still another feature is the provision of an adjustable side gage for aligning and laterally positioning the web.

A further feature is the provision of a novel severing device or knife.

The web is usually printed with a succession of similar forms, and is inserted bottom end first around the front of the platen and the bottom form on the web is typed. Then the web is withdrawn and the carbons are stripped from the typed form, and the latter then severed from the web, whereupon the web is reinserted at the front of the machine preparatory to typing the next form.

The carbons are retained by their rear ends by means of a set of holding blades, which are mounted upon the typewriter carriage. The carbons are interleaved between the plies of work-web and extend from the carbon-holder down in front of the platen and back under the same. As the platen is revolved at the line-spacing operations, the composite web idly forms a loop between the platen and the carbon-holder. Upon the completion of the typing of a form, the composite web is drawn out of the machine, and then extended forwardly in a straight line from the carbon-holder, thereby straightening out the sheets, and then the forward tips of the web-plies are grasped and said plies are pulled forwardly while the carbons remain stationary; this having the effect of separating the carbons from the typed forms and present-

ing them to fresh forms on the web. Then the web is reintroduced into the machine at the delivery side of the platen and the typed form is torn off, whereupon the web is guided down to the front of the platen and around under the same, preparatory to typing the next form.

In order to facilitate the handling of continuous forms, there is provided a bracket attachable to the end plates of the carriage-frame of the typewriting machine, and carrying at its upper end a paper-table, over which the webs may be fed and interleaved with carbon-sheets. The pack may then be inserted downwardly between guides carried by the bracket, and down into the machine at the front of the platen to the position of the first line of writing. After the first set of forms have been typed upon, the whole pack is removed from the machine and the webs are drawn forward, thereby stripping the carbons from the printed forms and simultaneously interleaving them with the next set of forms to be typed. The whole pack is then reinserted between the guide-plates, the printed forms severed and the pack inserted around the platen for the printing of the next set of forms.

Other features and advantages will hereinafter appear.

In the accompanying drawings,

Figure 1 is a cross-sectional view, in elevation, showing the invention applied to an Underwood standard typewriting machine.

Figure 2 is a fragmentary cross-sectional view, in elevation, showing the web being inserted around the platen, at the introductory side thereof.

Figure 3 is a cross-sectional view, in elevation, showing the web in a position to receive the first line of typing.

Figure 4 is a cross-sectional view, in elevation, through the line 4-4 of Figure 5.

Figure 5 is a front view, in elevation, of the invention applied to an Underwood standard typewriting machine.

Figure 6 is a view, partly in section, on the line 6-6 of Figure 1.

A web 10 is drawn up from a supply at the rear of the machine, and is passed over a rear paper-table 11, and then between carbon-holding blades 12, and is drawn forwardly between interleaving sheets of carbon-paper 13 fast to the blades 12. The

rear table 11 is fast to supporting brackets 14, which is in turn fast to a platen-frame 15 on which a platen 16 is revolvably mounted on a shaft 17. The carbon-blades are fast to the table 11 at the ends thereof by means of finger-screws 18.

The feed-rolls 19 are then released or moved away from the platen by means of a lever, not shown, and the interleaved web 20, shown in dot-and-dash lines in Figure 1, is inserted, leading edge first, down a chute 21. The chute comprises a front plate 22 and a rear plate 23 separated by a block 24, and the whole is fast by means of rivets 25 to two inwardly-extending ears 26 which form an integral part of the supporting brackets 14.

The leading edge of the interleaved web 20 is then gripped, as shown in Figure 2, and is pushed down the front side of the platen, and under the platen to co-operate with the feed-rolls, which may at this point be rendered effective to feed the web rearwardly, as shown in Figure 3, in which the web is in a position to receive the first line of typing thereon, by the action of the types 27.

Successive lines of typing may be printed upon the web, and successively the web is line-spaced while forming an idle loop 28, shown in Figure 3.

Upon completion of the typing of a form, the interleaved web is drawn out of the machine and is extended forwardly in a straight line from the carbon-holders to straighten out the sheets, and then the web is gripped by its leading edge, and is pulled forwardly while the carbons remain stationary, to thus separate the carbons from the typed forms and to present fresh forms to the carbon-sheets.

Due to the translucent nature of the paper used in this kind of webs, it is possible to see a dark portion forming a contrasting line 29 where the carbon-papers interleave the webs, which line may be matched with a line 30 printed upon the form. In this manner the web is pulled forwardly away from the carbon-holders until the line on the form coincides with the leading edge of the carbon-papers.

The interleaved web is then reinserted down the chute 21, and is pushed downwardly until a second line 31 printed on the web appears past a knife-edge 32, which may form an integral part of the front plate 22. Then the web is held with one hand over the rear plate 23 of the chute 21, and the typed forms are torn off against the knife.

After the severing of the typed forms, the fresh section of the web is reinserted in the machine at the front of the platen and around the same for the typing of the forms.

In order to facilitate the insertion of the leading edge of the web between the platen

and a guide-plate 33, a deflector 34, such as shown in the patent to J. A. B. Smith, No. 1,402,804, of January 10, 1922, may be used. The deflector 34 is fastened to brackets 35 and 36 by means of screws 37, and the brackets are in turn secured at 38 to the machine-frame 39.

Before inserting the interleaved web into the machine, it is desirable to first align the sheets. For this purpose, there is provided a gage-bar 40 slidably mounted between the plates 22 and 23. The bar 40 has an upwardly-projecting lug 41 which fits into a slot 42 in the plate 22. The bar is slidably adjustable in the slot 42, and may be held in any desired position by means of a thumb-screw 43.

Referring more particularly to Figure 5, it will be noted that the web extends over a portion of the platen only, to facilitate the front insertion of the web around the platen. The carriage is shown in its extreme right-hand position, in which the left-hand edge of the web clears the wing-scale 44 of the machine. Said scale 44 is fast to the frame 39 by means of the screws 45, and is provided with an outward flare 46, to facilitate the engaging of the web between the scale and the platen, when the carriage is letter-spaced. In order to position the gage 40 so that it will guide the edge of the web outside of the wing-scale when the carriage is moved to the left of the machine, the left-hand supporting bracket 14 is provided with an inwardly-extending bend 47, to thus bring the table 11 to the right of the carriage.

The carbon-holders are mounted upon the table in a manner indicated in Figure 6, in which there is shown spacing blocks 48 and 49, the latter being made narrower in order to permit the use of similar carbon-blades at both sides, and at the same time have them clearing one another. Upon the blocks 48 and 49, which are fast to the supporting brackets 14 by means of rivets 50, there are provided locating pins 51 fast to the blocks and extending upwardly through holes in the carbon-blades.

In order to facilitate the insertion of the interleaved web into the chute 21, the plates 22 and 23 have their longitudinal edges flared outwardly as at 52 with the crown of both flares in horizontal alignment with the carbon-holder, the flare of the plate 23 also serving as a deflector for the webs to prevent a shearing movement of the webs and carbons across the corners of the carbon-carrying blades.

It will be noted that the carbon-carrier is fixed to a stationary part of the carriage and the holder is never disturbed except to replace exhausted carbon-sheets; that the relative location of the carbon-holder to the printing area of a work-web-section is such that when the lower carbon-sections become

exhausted, the exhausted sections may be reversed end for end with the upper unused carbon-sections, and in this manner the whole carbon-area of the sheet or sheets may 5 be utilized without waste; that this mode of operation of line-spacing the webs and carbons out of the machine to be subsequently straightened out to the horizontal plane of the carbon-holder, and the webs drawn forwardly 10 away from stationary carbon-inlays, results in a comparatively simple and efficient mechanism to accomplish a more or less complicated manifold typing operation, with a minimum degree of crocking from the 15 rubbing faces of the carbon-inlays; that the slack in the web develops into a loop as the line-spacing of the web progresses and the loop so formed is deflected rearwardly over the platen and through the clearance space 20 between the chute and the platen, thus rendering the typed records on the web visible to the operator; and that were the rear plate 23 of the chute extended to the platen position, to close up this gap, the loop 28 of 25 Figure 3 would be forced outwardly towards the operator and only a few of the typed lines would be visible.

Variations may be resorted to within the scope of the invention, and portions of the 30 improvements may be used without others.

Having thus described my invention, I claim:

1. In a typewriting machine having a revoluble platen, a platen-frame and typing 35 instrumentalities, means for presenting to the platen a web including work-plies interleaved with carbons in a manner to afford typing of the bottom form on the web preparatory to severing the typed form and 40 presenting the next form to the platen, said means having, in combination, a carbon-holder secured as a carbon-unit to the platen-frame to be stationary at all times relatively thereto, the plies of work-web being threaded 45 between the carbons, and means adjacent the front of the carbon-holder for deflecting and guiding downwardly to the platen, forwardly of its axis, the leading end of the web; the web forming an idle loop at the 50 delivery side of the platen during the line-spacing operation.

2. In a typewriting machine having a revoluble platen, a platen-frame and typing 55 instrumentalities, means for presenting to the platen a web including work-plies interleaved with carbons in a manner to afford typing of the bottom form on the web preparatory to severing the typed form and 60 presenting the next form to the platen, said means having, in combination, a carbon-holder secured as a carbon-unit to the platen-frame to be stationary at all times relatively thereto and located above the platen, the 65 plies of work-web being threaded between the carbons, means adjacent the front of the

carbon-holder for deflecting and guiding downwardly to the platen, forwardly of its axis, the leading end of the web; the web forming an idle loop at the delivery side of the platen during the line-spacing operation, and relatively stationary means between the platen and the carbon-holder for severing the web. 70

3. In a typewriting machine having a revoluble platen, a platen-frame and typing 75 instrumentalities, means for presenting to the platen a web including work-plies interleaved with carbons in a manner to afford typing of the bottom form on the web preparatory to severing the typed form and 80 presenting the next form to the platen, said means having, in combination, a carbon-holder secured as a carbon-unit to the platen-frame to be stationary at all times relatively thereto, the plies of work-web being threaded 85 between the carbons, means adjacent the front of the carbon-holder for deflecting and guiding downwardly to the platen the leading end of the web; the web forming an idle loop at the delivery side of the platen during the line-spacing operation, means between the platen and the carbon-holder for 90 severing the web, the web being withdrawable from the platen after typing of the bottom form thereon to be extended forwardly from said carbon-holder to straighten out the composite web preparatory to stripping the carbons, by pulling forward the web-plies while the carbons are held stationary by the carbon-holder, and means 95 located approximately on a level with said carbon-holder for supporting said web stationary with respect to the platen during the line-spacing movement of the latter. 100

4. A typewriting machine including a revoluble platen and feed-rolls therefor, a line-spacing mechanism, and means for deflecting an elongate web, bottom end first, downwardly to the platen, forwardly of its axis, to a platen-feeding position, said means including a chute disposed above said platen, the lowermost edge of the chute being spaced a sufficient distance from the top of the platen to permit the slack in the web, produced by the line-spacing, to form a rearwardly extending loop of large radius so as 110 to keep the typed portion of the web visible to the operator. 115

5. A typewriting machine including a platen-frame, a revoluble platen and feed-rolls therefor, a line-spacing mechanism, means for deflecting an elongate web, bottom end first, downwardly to the platen, forwardly of its axis, said means including a chute overlying said platen for conducting the web prior to its introduction into the machine, the lowermost edge of said chute being sufficiently spaced from said platen to provide a space to receive the slack loop in the web between the chute 125 130

and the platen during the line-spacing of the web, and means for supporting the upper portion of the web stationary, relatively to said platen, during the line-spacing movement thereof.

6. A typewriting machine including a platen-frame, a revoluble platen and feed-rolls therefor, a line-spacing mechanism, means for deflecting a horizontally-disposed web, bottom end first, to the platen, said means including a chute overlying said platen for conducting the web prior to its introduction into the machine, means for attaching said chute to the platen-frame in a manner to form an open backless section for the web between the chute and the platen to provide for a slack loop in the web developed by the line-spacing of the web, and means for supporting the upper portion of the web stationary, relatively to said platen, during the line-spacing movement thereof.

7. A typewriting machine including a revoluble platen and feed-rolls therefor, a line-spacing mechanism, and means for deflecting a horizontally-disposed web, bottom end first, to the platen, said means including a chute overlying said platen and at the rear thereof for conducting the web downward and forward towards the platen prior to its introduction into the machine and over a web-clearance gap between the chute and the platen to enable the slack in the web during the line-spacing thereof to develop a loop that is guided within said gap.

8. In a typewriting machine having a revoluble platen, a platen-frame, a wing scale in front of the platen, and typing instrumentalities, means for presenting to the platen a web including work-plies interleaved with carbons in a manner to afford typing of the bottom form on the web preparatory to severing the typed form and presenting the next form to the platen, said means having, in combination, a carbon-holder secured as a carbon-unit to the platen-frame to be stationary relatively thereto during the line-spacing operation, the plies of work-web being threaded between the carbons, means at the front of the platen to the right of the wing scale for guiding downwardly around the same the leading end of the web; and an introductory device being provided between said carbon-holder and the platen for guiding the bottom edge of the web to the platen said introductory device being mounted on the platen-frame.

9. In a typewriting machine having a revoluble platen, a platen-frame and typing instrumentalities, means for presenting to the platen a web including work-plies interleaved with carbons in a manner to afford typing of the bottom form on the web preparatory to severing the typed form and presenting the next form to the platen, said means having, in combination, a carbon-

holder secured as a carbon-unit to the platen-frame to be stationary relatively thereto during the line-spacing operation, the plies of work-web being threaded between the carbons, means at the front of the carbon-holder 70 for deflecting downwardly to the platen, forwardly of its axis, the leading end of the web; the web forming an idle loop at the delivery side of the platen during the line-spacing operation, and means between the 75 platen and the carbon-holder for severing the web, including a straight stationary knife which co-operates with the deflecting means to promote the severing of the typed web-section.

10. In a typewriting machine including a platen-frame, a platen, feed-rolls therefor, and a line-spacing mechanism, in combination, means for interleaving a continuous web with sheets of carbon-paper including a plurality of stationary carbon-holders, means for first deflecting and then guiding the interleaved web down a chute towards the front of the platen, means for facilitating the insertion of the web at the delivery side 90 of platen, whereby the web may be fed rearwardly around the platen to the initial line of print, and then line-spaced forwardly 95 step by step as lines are typed upon the web, the line-spacing of the web creating a slack in the web, and a clearance opening in the platen-frame to provide for the loop developed from the slack in the line-spaced web.

11. In a typewriting machine including a platen, feed-rolls therefor, and a line-spacing mechanism, in combination, means for interleaving a continuous web with sheets of carbon-paper including a plurality of carbon-holders, means for first deflecting and then guiding the interleaved web down through a chute towards the front of the platen, means for facilitating the insertion of the web at the delivery side of the platen, whereby the web may be fed rearwardly around the platen and then line-spaced forwardly as lines are typed upon the web, and means for severing the web, including a knife edge forming an integral part of the chute and co-operating with the chute to promote a web-severing operation.

12. In a typewriting machine including a platen and feed-rolls therefor, in combination, means for interleaving a continuous web with sheets of carbon-paper including a plurality of carbon-holders to which the carbon-sheets are fast, means for guiding the interleaved web down a chute at the front of the platen, means for facilitating the insertion of the web at the delivery side of the platen, whereby the web may be fed rearwardly around the platen and then line-spaced forwardly as lines of typing are printed upon the web, means for severing the web, and means for laterally guiding the web previous to the introduction of the web 120 125 130

around the platen, said last-mentioned means including a slidably-mounted piece within the chute, and means for manually positioning and locking in place said slidably-mounted piece.

13. In a typewriting machine including a platen-frame, a platen and feed-rolls therefor to feed a work-web around the platen in either direction, a chute over the platen to direct the web to the platen for a rearward platen-feeding movement, a line-spacing mechanism to advance the web step by step in typing, and a supporting frame for the chute secured to the platen-frame and constructed to provide an unobstructed space above the platen to permit the line-spaced slack in the typed web to collect in a loop towards the rear of the platen.

14. In a typewriting machine including a revoluble platen and a platen-frame, feed-rolls co-operating with said platen to feed a web interleaved with sheets of carbon, means for holding the sheets of carbon by their rear ends, said means being fixed relatively to the platen, and a chute for guiding the web between the means for holding the carbons and the platen, said chute comprising a front and a rear plate, the front plate forming a cutting edge at its lowermost edge, and the rear plate serving as a backing for the web while being torn off.

15. In a typewriting machine including a revoluble platen and a platen-frame, feed-rolls co-operating with said platen to feed a web interleaved with sheets of carbon, and blades for holding the sheets of carbon by their rear ends, said blades being fixed relatively to the platen, and comprising supporting brackets fast to the platen-frame upon which the carbon-holding blades are mounted, said carbon-holding blades being manually attachable to a rear table, and the rear table being also supported by the brackets.

16. In a typewriting machine including a revolubly-mounted platen and manually-controllable feed-rolls therefor, in combination, means including a paper-table to guide a manifold web from a web supply at the rear of the machine, means including carbon-blades for interleaving the plies of the webs with sheets of carbon and for holding the carbons suspended by one of their ends from a fixed frame overlying the platen, means forming a part of a chute to deflect the interleaved web down to the chute and towards the front of the platen, and means including a stationary guide for directing the insertion of the web around the platen at the front side thereof.

17. In a typewriting machine including a revolubly-mounted platen and manually-controllable feed-rolls therefor, in combination, means including a paper-table to guide a manifold web from a web-supply at the

rear of the machine, means including carbon-blades for interleaving the plies of the webs with sheets of carbon and for holding the carbons suspended by one of their ends from a fixed frame overlying the platen, 70 means forming a part of a chute to deflect the interleaved web to the chute and towards the front of the platen, means including a stationary guide for directing the insertion of the web around the platen at 75 the front side thereof, means for feeding the web rearwardly to the initial typing position, and means for line-spacing the interleaved web forwardly, the web forming an idle loop at the front side of the platen 80 during the line-spacing operation.

18. In a typewriting machine including a revolubly-mounted platen and manually-controllable feed-rolls therefor, in combination, means including a paper-table to guide a manifold web from a web-supply at the rear of the machine, means including carbon-blades for interleaving the plies of the webs with sheets of carbon and for holding the carbons suspended by one of their ends from a fixed frame overlying the platen, 85 means forming a part of a chute to deflect the interleaved web to the chute and towards the front of the platen, means including a stationary guide for directing the insertion of the web around the platen at 90 the front side thereof, means for feeding the web rearwardly to the initial typing position, and means for line-spacing the interleaved web forwardly, the web forming an idle loop at the front side of the platen 95 during the line-spacing operation, the bottom of the chute being sufficiently spaced from the platen to permit the loop so formed to project rearwardly over the platen, to 100 render the typed record thereon visible to the operator.

19. In a typewriting machine having a revoluble platen and a platen-frame, means for presenting a work-web to the printing field bottom end first, said means including a chute for guiding the web at the front of the platen, means at the delivery side thereof for facilitating the introduction of the web, and means forming an integral part of the chute 110 for severing the web, said last-mentioned means comprising a cutting edge at the bottom side of the chute, and a backing plate adjacent the cutting edge for supporting the web while being torn off against the cutting edge.

20. In a typewriting machine having a revoluble platen and a platen-frame, means for presenting a work-web to the printing field bottom end first, said means including a chute for guiding the web at the front of the platen, means at the delivery side thereof for facilitating the introduction of the web, and means forming an integral part of the chute for severing the web, said last-men- 125 130

tioned means comprising a cutting edge at the bottom side of the chute, a backing plate adjacent the cutting edge for supporting the web while being torn off against the cutting edge, and means for holding a plurality of interleaving carbon-sheets above the chute, said last-mentioned means comprising clamping blades fast to a supporting bracket at the ends of the platen-frame.

10 21. In a typewriting machine having a platen revolvably mounted on a traveling carriage and a paper-guide in front of the platen and fixed to a stationary part of the frame of the machine, centrally thereof, the combination of a carbon-holder arranged to interleave with carbons, a plurality of work-plies, a chute overlying said platen and arranged to direct said plurality of work-plies to the forward face of the platen, said chute being mounted on said carriage and offset to the right with respect to the center line of said carriage so that, when the carriage is at the right of the machine, the left edge of said chute will be to the right of the right edge of said guide to permit the ready insertion of the work-plies under and rearwardly of the platen, the carbon-holder being stationary relatively to said chute, and the left edge of said holder being in line with

the left edge of said chute, and an additional 30 guide in front of the machine to facilitate such front insertion.

22. In a typewriting machine having a platen, a platen-frame, and typing and line-spacing mechanism, means for directing a plurality of continuous work-plies interleaved with carbons to the forward face of said platen to be fed under and rearwardly thereof, and means for supporting the upper portions of said work-plies stationarily with 35 respect to said platen during the line-space movement thereof so as to cause a slack loop to form in said work-plies between said supporting means and said platen.

23. In a typewriting machine having a platen-frame and a platen journaled therein, the combination of an enclosed chute including front and rear plates mounted on the platen-frame above said platen and disposed to direct a plurality of work-webs 40 interleaved with carbons downwardly toward the front face of the platen to be fed rearwardly thereunder, an adjustable side gage located in said chute, the upper edges of said plates being bent away from each 45 other, and a knife disposed at the lower edge 50 of the chute.

BURNHAM C. STICKNEY.
